[57] ABSTRACT

[57] **ABSTRACT**
An electromagnetic actuating device controls functional operations in a keyboard printer. In the printer, movement of each operational interposer is controlled by a lightweight armature plate having an adjustable actuating rod which when the electromagnetic means for each armature plate is energized will operate upon the end of an interposer to release the interposer to perform a selected functional operation in the printer, such as, "tab," "backspace," "space," "index" or "return"; and, when deenergized, the armature plate will follow the return movement of the interposer to its original disposition in preparation for the next functional operation without the aid of a special return mechanism.

OPERATIONAL INPUT CONTROL MECHANISM

This invention relates to a novel and improved mechanism for automatically selected different functional operations to be performed in a business machine, and more particularly relates to an electromagnetic actuating device for electrically controlling functional operations in a keyboard printer, typewriter and the like.

In the keyboard printer art, it is customary to employ a combination of manual and automatic actuating means for selectively releasing an operational interposer to perform a given functional operation. Typical functional operations in a keyboard printer include "tab," "backspace," "space," "index," and "return." Commonly, the interposer or other linkage elements for each operation includes a releasable latch which normally retains the interposer elements in a normally inoperative or locked position; and the manual or automatic actuating means is engageable either with the latch or interposer to unlatch the interposer to perform a selected operation. In accordance with the present invention, the automatic actuating means is engageable at the end of the interposer or latch member in order to effect maximum leverage and in such a way as to accurately follow return movement of the interposer to its latched position without the use of separate return means; further, the automatic actuating means is made up of a minimum number of parts occupying the least amount of space and each actuating means is readily adjustable and capable of direct positive actuation of the interposer with which it is associated.

It is therefore an object of the present invention to provide novel and improved automatic actuating means for selectively and automatically controlling functional operations in keyboard printers and the like in a dependable and highly efficient manner.

It is another object of the present invention to provide for electromagnetic actuating means which is directly engageable with the end of each interposer in the operational control linkage in order to control a functional operation in a keyboard printer, such as, the functions of "tab," "space," "backspace," "index" and "return," to automatically but selectively release the interposer in response to an applied electrical signal, and to closely follow return movement of the interposer to its latched position.

It is a further object of the present invention to provide an operational input assembly for a keyboard printer in which the mass and size of armature control plates are minimized and adjustable actuating rods are responsive to movement of the armature plates to operate upon the ends of operational interposers to release same in performing selected functional operations, and, when deenergized, the rods and plates will follow return movement of the interposers to their original locked positions in preparation for the next functional operation.

In accordance with the present invention, an electromagnetic actuating device controls functional operations of a keyboard printer through an armature plate and a threadedly adjustable actuator rod directly engageable with a pivotal latch at the free end of an interposer. The latch, being normally secured, latches the interposer in an inoperative position and is pivotal away from the latched position to free the interposer to carry out a desired function. Typical of the interposer construction is that utilized for manual selection in the IBM Selectric typewriter which has an interposer man-

ually engageable to release an associated pivotal latch. In the present invention, the interposer and associated latch are selectively released in response to an electrical control signal applied to a solenoid for each operation to be performed. The solenoids are mounted in a common open housing, and a flat, lightweight armature plate for each interposer is extended across the open end of the housing, the plate extending loosely through slots in opposite sides of the housing, and the actuator rod extends from the opposite end for engagement with the free end of the latch. Each plate operates on an interposer through its actuator rod in releasing the latch, and the rod remains in contact with the latch in following return movement of the interposer to the original locked position.

The above and other objects, advantages and features of the present invention will become more readily appreciated and understood from a consideration of the following detailed description when taken together with the accompanying drawing, in which:

FIG. 1 is a perspective view of the preferred form of operational input mechanism in accordance with the present invention, the mechanism shown mounted on the underside of a typewriter but illustrated in a position rotated 90° counterclockwise.

FIG. 2 is a top plan view of the preferred form of operational input mechanism.

FIG. 3 is a side elevational view illustrating the relative disposition between parts comprising the operational input mechanism.

FIG. 4 is a view in detail of the latch and actuating rod portions of the operational input mechanism; and

FIG. 5 is a fragmentary sectional view to the latch mounting in the frame taken along line 5-5 of FIG. 3.

Referring in more detail to the drawing, there is shown by way of illustrative example in FIGS. 1 to 5 a preferred form of operational input control mechanism which is particularly adaptable for use in controlling the functional operations of a keyboard printer, for example, of the type referred to as an input/output typewriter. A typical typewriter unit is the Selectric I/O Keyboard Printer manufactured by International Business Machines (IBM). The IBM Selectric has a plurality of operational modes including "index," "tab," "carrier return," "space" and "backspace" and in manual keyboard operations each functional operation is activated by a separate operational interposer or control lever, a portion of which is designated at 10 in FIG. 3. Each operational interposer 10 includes an elongated, slidable arm member 12 provided with a pivotal latch 13 which is pivotal about a pivot pin 14 inwardly of the free end of the interposer 10 and is provided with a shoulder or ledge 15, shown in detail in FIG. 4. Normally, the latch 13 is biased by a spring element 16 into an inoperative position by engagement of the shoulder 15 with a stationary latch plate 17. The outer extremity 18 of the interposer 10 is also provided with a downwardly inclined, laterally extending or bent tab portion 19 which in manual operations is selectively engaged

by a bent portion 20 on a manual release member, here represented at R, so as to effect pivotal movement of the interposer 10 about its opposite pivotal end, not shown, until the shoulder 15 clears the latch plate 17 and the interposer 10 is free to slide longitudinally in the direction of the arrow to initiate a selected functional operation through the control mechanism of the printer. Thus, an operational interposer 10 and associ-

ated latch 13 and release mechanism R is provided for each functional operation and each is independently controllable to select its corresponding functional operation all in a well-known manner. Moreover, in manual operations, the operational interposers 10 selected in performing given functional operations are returned to their original disposition at the end of the operating cycle and the latch 13 automatically returned to its latch disposition by the return spring 16; and in turn the release members R are reset by a reset bail 22 which is pivotal about a shaft 23 journaled at opposite ends in spaced carrier brackets 24. One end of the shaft 23 is connected to a pivot arm 25 whose opposite end is secured by clevis 26 to a control rod 27 operated off of a timing switch, not shown, but which is set forth and described in more detail in my copending application for patent, Ser. No. 75,982, filed Sept. 28, 1970, and assigned to the assignee of the present invention. In a manner not shown, the control rod 27 will cause outward pivotal movement of the reset bail 22 against extensions R' of the release members R to return the release members R to their original dispositions.

When the Selectric I/O Keyboard Printer is energized automatically to print out information from a remote station, such as, a reader, by the transmission of electrical signals representing the information to the printer, the operational input control or selector mechanism of the present invention similarly must be selectively controlled to perform functional operations in correlation with the matter being printed. To this end, signal-responsive means comprises a series of operational input solenoids 28 which, as shown in FIGS. 2 to 4, are arranged in side-by-side relation to one another in a common, generally U-shaped housing 29 which is attached by a mounting bracket 30 to frame portion 31 of the typewriter. As illustrated, the housing 29 is in the form of a generally U-shaped channel having a closed end portion 32 and opposite sides 33 and 34 with the side portion 33 suitably attached by connecting screws 35 to the mounting bracket 30, the latter extending perpendicularly from its connection to the frame 31. In connected relation, the open end of the housing 29 is in the facing relation to the frame portion 31 and the side portion 34 of the housing 29 includes an extension plate 37 mounted by connecting screws 38 to the external surface of the side portion 34.

A plurality of solenoids 28 are mounted in the solenoid housing 29, one for each functional operation to be performed, and the solenoids 28 are arranged with their pole pieces 40 projecting from the open end of the channel in facing relation to the frame 31, each of the solenoids 28 adapted to independently control unlatching of an operational interposer 10 through latch control means generally designated at 42 and presently to be described. The latch control mechanism 42 for each operational interposer 10 and associated latch 13 includes an armature plate 44 which is mounted on the solenoid housing 29 for extension across the exposed end of each pole piece 40. Aligned pairs of slots 45 and 46 are exposed at spaced intervals along the length of opposite sides 33 and 34 of the solenoid housing, there being a series of slots 45 at spaced intervals in the side 33 of the housing 29 and a plurality of slots 46 at correspondingly spaced intervals along the extension plate 37 outwardly of the free or open end of the side portion 34. Each armature plate 44 is relatively flat and elongated for extension from a seating slot 30' through an

aligned pair of slots 45 and 46 with one end of the armature plate notched as at 48 to be loosely secured within a slot 45. The intermediate part of each plate 44 extends through a slot 46 and an outward extension 49 projects beyond the housing 29 in spaced parallel relation to an interposer 10. The outermost extremity of the armature plates 44 terminate in a laterally offset portion 50 which is aligned opposite to the latch 13 of its respective interposer 10 and serves as a support for 10 an actuator rod or control arm 52 extending normal to the plate 44. Each actuator rod 52 has a threaded end 53 passed through an aperture 51 in the offset portion 50 which is adjustably secured by a pair of lock nuts 54 and 55; and further the opposite end of the rod 52 is in 15 the form of a generally U-shaped or hooked end portion 56 which is passed over the end of the latch 13 and into engagement with the latch 13 directly behind its shoulder 15.

As illustrated in FIGS. 1 and 2, when an electrical signal is applied to each solenoid coil, energization of the solenoid 28 will cause its armature plate 44 to be drawn inwardly toward the pole piece 40. The actuator rod 52 will follow movement of the plate 44 to draw the latch 13 away from its latched position with respect to the 20 latch plate 17 and permit slidable movement of the interposer 10 as described. The particular distinct advantages in utilizing the actuator rod 52 as disclosed and illustrated are that it minimizes the size and weight of the entire mechanism as well as the number of adjustments required in mounting the operational input control mechanism on the printer unit, since the hooked end portion 56 of the rod 52 simply can be passed over the end of the latch 13 into position behind the shoulder 15 and its threaded end 53 tightened to draw the hooked end portion 56 against the underside of the latch 13 when the armature plate 44 is normally disposed away from the solenoid 28. In addition, the armature plate 44 will closely follow return movement of the latch 13 to its latched position, under the urging of 25 the spring 16 at the end of each operational cycle, thereby obviating the use of a special return mechanism for the armature plate 44 and latch control rod 52.

When the input control mechanism is installed, the 45 mounting bracket 30 is first attached to the frame 31 and the solenoid housing 29 affixed to the bracket 30 with the armature plates 44 extending in spaced parallel relation to the interposers 10 and the rods 52 secured to the latches 13. The desired close adjustment 50 is afforded through tightening of the actuator rods 52 by the lock nuts 54 and 55, and enlarged slots, not shown, may be provided on the mounting bracket 30 for adjustable attachment between the bracket 30 and side portion 33 of the housing 29 so that the proper 55 spacing is established between the armature plates 44, solenoid cores 28 and the ends of the interposers 10. Further, it is desirable to apply a strip of plastic 60 over the exposed ends of the pole pieces 40 to minimize effects of residual magnetism and this strip 60 may suitably be composed of Mylar or Teflon to maintain the necessary air gap between the plates 44 and pole pieces 40. In addition, a flux return path is established between the solenoid housing 29 and typewriter through the mounting bracket 30 to the frame 31. When an 60 electrical signal is applied to any one or more of the solenoids 28, the associated armature plate 44 is drawn inwardly against the core of the solenoid 28 to draw the 65

latch 13 away from the latch plate 17 and permit the interposer 10 to be activated to perform the desired functional operation. Any one or more desired functional operations may be effected simultaneously; and, as previously stated, at the end of the operational cycle each activated interposer 10 will automatically reset its associated armature plate 44 to the original disposition away from the solenoid 28 in preparation for the next functional operation. The slots 45, 46 are dimensioned to prevent lateral displacement of the armature plates 44 while permitting the plates 44 to rock the limited distance necessary to control movement of the actuator rods 52, the end of the side portion 34 limiting inward movement of the plates 44 to the extent necessary to release the latch 13.

From the foregoing, it will be evident that the operational input control mechanism of the present invention employs a relatively lightweight latch control means which greatly minimizes the size and weight of the armature plates 44 and rods 52 as well as the amount of movement or "throw" necessary to release a selected interposer 10. This is important in reducing the force curve of the solenoid 28 which increases sharply with increases in the amount of throw or movement of the armature plate 44. Additionally, closer adjustment is afforded through independent adjustability of the actuator rods 52 which again operate upon the pivotal latch members 13, as opposed to the end of the interposer 10, and are not affected by and do not interfere with the manual operation of the printer unit.

It is therefore to be understood that various modifications and changes may be made in the detailed construction and arrangement of parts comprising the preferred form of the present invention without departing from the spirit and scope thereof.

I claim:

1. In a keyboard printer having a plurality of operational control interposers arranged in closely spaced, juxtaposed relation to one another, each operational control interposer having a free end and being independently swingable from a normally inoperative position to an operative position to perform a selected functional operation, each operational control interposer having a pivotal latch member provided with a free end spaced inwardly of the free end of said interposer and engageable with a stationary latch plate to releasably latch the operational control interposer against movement, a spring return member connected between each said operational control interposer and said pivotal latch member biased to urge the pivotal latch member into engagement with the latch plate whereby to latch the interposer in the inoperative position, an operational input mechanism for selectively effecting release of each of said pivotal latch members from said latch plate in controlling each of a plurality of functional operations, said mechanism comprising:

electromagnetic actuating means including a common housing mounted on said printer with an open end of said housing aligned in spaced, facing relation to said interposers, and a plurality of solenoids in said housing disposed in closely spaced, juxtaposed relation, there being a solenoid for each of said interposers,

an armature plate for each of said solenoids disposed across the open end of said housing in spaced, substantially parallel relation to one of said interposers, each armature plate loosely disposed in slots in

opposite sides of said housing for movement toward and away from said interposers under the influence of said solenoids and each armature plate extending beyond a slot in one side of the housing to terminate in a free end aligned in spaced relation to a respective pivotal latch member, and

an actuating rod extending normally from each armature plate including one end adjustably connected to the free end of said armature plate externally of said housing, the opposite end of each actuating rod engageable with each pivotal latch member inwardly of the free end of each associated interposer for selectively releasing the pivotal latch member when an associated solenoid is energized and the armature plate is moved away from the interposer in advancing the interposer from the inoperative to the operative position upon energization of each associated solenoid, and the interposer being returned to the inoperative position and the pivotal latch member engaging the latch plate to cause the actuating rod to move the armature plate toward the interposer solely under the urging of said spring return member when each associated solenoid is deenergized.

2. In a keyboard printer according to claim 1, the opposite end of said actuating rod having a bent lever-engaging portion engageable with the pivotal latch member.

3. In a keyboard printer according to claim 2, the one end of said actuating rod being threaded for extension through an opening in said free end of said armature plate beyond the side of said common housing, and lock nuts threadedly disposed on the threaded end of said actuating rod to position the lever-engaging portion of said actuating rod in engagement with the armature plate, and the opposite end of said actuating rod having said bent lever-engaging portion formed as a generally U-shaped return disposed for engagement with said pivotal latch member.

4. In a keyboard printer according to claim 1, each armature plate being rockable about the edge of the slot most removed from said actuating rod, and a plastic tape covering the ends of said solenoids beneath said armature plate, flat and elongated for extension from a seating slot 30' through an aligned pair of slots 45 and 46 with one end of the armature plate notched as at 48 to be loosely secured within a slot 45. The intermediate part of each plate 44 extends through a slot 46 and an outward extension 49 projects beyond the housing 29 in spaced parallel relation to an interposer 10. The outermost extremity of the armature plates 44 terminate in a laterally offset portion 50 which is aligned opposite to the latch 13 of its respective interposer 10 and serves as a support for an actuator rod 94 control arm 52 extending normal to the plate 44. Each actuator rod 52 has a threaded end 53 passed through an aperture 51 in the offset portion 50 which is adjustably secured by a pair of lock nuts 54 and 55; and further the opposite end of the rod 52 is in the form of a generally U-shaped or hooked end portion 56 which is passed over the end of the latch 13 and into engagement with the latch 13 directly behind its shoulder 15.

As illustrated in FIGS. 1 and 2, when an electrical signal is applied to each solenoid coil, energization of the solenoid 28 will cause its armature plate 44 to be drawn inwardly toward the pole piece 40. The actuator rod 52 will follow movement of the plate 44 to draw the latch

13 away from its latched position with respect to the latch plate 17 and permit slidable movement of the interposer 10 as described. The particular distinct advantages in utilizing the actuator rod 52 as disclosed and illustrated are that it minimizes the size and weight of the entire mechanism as well as the number of adjustments required in mounting the operational input control mechanism on the printer unit, since the hooked end portion 56 of the rod 52 simply can be passed over the end of the latch 13 into position behind the shoulder 15 and its threaded end 53 tightened to draw the hooked end portion 56 against the underside of the latch 13 when the armature plate 44 is normally disposed away from the solenoid 28. In addition, the armature plate 44 will closely follow return movement of the latch 13 to its latched position, under the urging of the spring 16 at the end of each operational cycle, thereby obviating the use of a special return mechanism for the armature plate 44 and latch control rod 52.

When the input control mechanism is installed, the mounting bracket 30 is first attached to the frame 31 and the solenoid housing 29 affixed to the bracket 30 with the armature plates 44 extending in spaced parallel relation to the interposers 10 and the rods 52 secured to the latches 13. The desired close adjustment is afforded through tightening of the actuator rods 52 by the lock nuts 54 and 55, and enlarged slots, not shown, may be provided on the mounting bracket 30 for adjustable attachment between the bracket 30 and side portion 33 of the housing 29 so that the proper spacing is established between the armature plates 44, solenoid cores 28 and the ends of the interposers 10. Further, it is desirable to apply a strip of plastic 60 over the exposed ends of the pole 40 to minimize effects of residual magnetism and this strip 60 may suitably be composed of Mylar or Teflon to maintain the necessary air gap between the plates 44 and pole pieces 40. In addition, a flux return path is established between the solenoid housing 29 and typewriter through the mounting bracket 30 to the frame 31. When an electrical signal is applied to any one or more of the solenoids 28, the associated armature plate 44 is drawn inwardly against the core of the solenoid 28 to draw the latch 13 away from the latch plate 17 and permit the interposer 10 to be activated to perform the desired functional operation. Any one or more desired functional operations may be effected simultaneously; and, as previously stated, at the end of the operational cycle each activated interposer 10 will automatically reset its associated armature plate 44 to the original disposition away from the solenoid 28 in preparation for the next functional operation. The slots 45, 46 are dimensioned to prevent lateral displacement of the armature plates 44 while permitting the plates 44 to rock the limited distance necessary to control movement of the actuator rods 52, the end of the side portion 34 limiting inward movement of the plates 44 to the extent necessary to release the latch 13.

From the foregoing, it will be evident that the operational input control mechanism of the present invention employs a relatively lightweight latch control means which greatly minimizes the size and weight of the armature plates 44 and rods 52 as well as the amount of movement or "throw" necessary to release a selected interposer 10. This is important in reducing the force curve of the solenoid 28 which increases

sharply with increases in the amount of throw or movement of the armature plate 44. Additionally, closer adjustment is afforded through independent adjustability of the actuator rods 52 which again operate upon the pivotal latch members 13, as opposed to the end of the interposer 10, and are not affected by and do not interfere with the manual operation of the printer unit.

It is therefore to be understood that various modifications and changes may be made in the detailed construction and arrangement of parts comprising the preferred form of the present invention without departing from the spirit and scope thereof.

I claim:

1. In a keyboard printer having a plurality of operational control interposers arranged in closely spaced, juxtaposed relation to one another, each operational control interposer having a free end and being independently swingable from a normally inoperative position to an operative position to perform a selected functional operation, each operational control interposer having a pivotal latch member provided with a free end spaced inwardly of the free end of said interposer and engageable with a stationary latch plate to releasably latch the operational control interposer against movement, a spring return member connected between each said operational control interposer and said pivotal latch member biased to urge the pivotal latch member into engagement with the latch plate whereby to latch the interposer in the inoperative position, an operational input mechanism for selectively effecting release of each of said pivotal latch members from said latch plate in controlling each of a plurality of functional operations, said mechanism comprising:

electromagnetic actuating means including a common housing mounted on said printer with an open end of said housing aligned in spaced, facing relation to said interposers, and a plurality of solenoids in said housing disposed in closely spaced, juxtaposed relation, there being a solenoid for each of said interposers,

an armature plate for each of said solenoids disposed across the open end of said housing in spaced, substantially parallel relation to one of said interposers, each armature plate loosely disposed in slots in opposite sides of said housing for movement toward and away from said interposers under the influence of said solenoids and each armature plate extending beyond a slot in one side of the housing to terminate in a free end aligned in spaced relation to a respective pivotal latch member, and

an actuating rod extending normally from each armature plate including one end adjustably connected to the free end of said armature plate externally of said housing, the opposite end of each actuating rod engageable with each pivotal latch member inwardly of the free end of each associated interposer for selectively releasing the pivotal latch member when an associated solenoid is energized and the armature plate is moved away from the interposer in advancing the interposer from the inoperative to the operative position upon energization of each associated solenoid, and the interposer being returned to the inoperative to cause the actuating rod to move the armature plate toward the interposer solely under the urging of said spring return member when each associated solenoid is deenergized.

2. In a keyboard printer according to claim 1, the opposite end of said actuating rod having a bent lever-engaging portion engageable with the pivotal latch member.

3. In a keyboard printer according to claim 2, the one end of said actuating rod being threaded for extension through an opening in said free end of said armature plate beyond the side of said common housing, and lock nuts threadedly disposed on the threaded end of said actuating rod to position the lever-engaging portion of said actuating rod in engagement with the arma-

ture plate, and the opposite end of said actuating rod having said bent lever-engaging portion formed as a generally U-shaped return disposed for engagement with said pivotal latch member.

4. In a keyboard printer according to claim 1 each armature plate being rockable about the edge of the slot most removed from said actuating rod, and a plastic tape covering the ends of said solenoids beneath said armature plate.
